Inventor:

Elijah M. Bosley

United States Patent Office.

ELIJAH M. BOSLEY, OF BALTIMORE, MARYLAND.

Letters Patent No. 102,757, dated May 10, 1870.

STEAM-HEATING APPARATUS.

The Schedule referred to in these Letters Patent and making part of the same.

To all whom it may concern:

Be it known that I, ELIJAH M. BOSLEY, of the city and county of Baltimore, Maryland, have invented certain new and useful Improvements in Steam-heating Apparatus; and do hereby declare that the following is a full, clear, and exact description thereof, reference being had to the accompanying drawings and to the letters of reference marked thereon making a part of this specification.

In the drawings—

Figure 1 represents a vertical section.

Figure 2 represents a plan view with the top removed.

The object of my invention is to obtain the greatest possible amount of heating surface in the smallest space, and with great saving of fuel.

It consists in a peculiar arrangement of fire and water flues, more particularly shown in the drawings, and described in this specification.

It also consists in forming the boiler of a number of sections bolted together by flanges or their equivalents.

In the accompanying drawings—

A represents a hollow rectangular cylinder made in sections and bolted together, as plainly shown at *a a*.

The lower section B represents the ash-pit, made with an opening for the final outlet S of the smoke to the chimney.

Bolted to this section is the section C, in the lower part of which is arranged the grate I.

The following section D is provided with pipes K running from side to side of cylinder A and at right angles to the grate.

It is also provided with the feed-opening R for supplying the water.

The next following sections, E F G, are likewise provided with pipes K' K" K'', each set being arranged at right angles to each other.

The uppermost section H is the steam-drum, from which the steam passes through the openings Q Q to any desired place or receptacle.

In this section is arranged the outlet N, provided with the damper O.

The sections are all connected with each other by the openings P. These holes may, however, be made in one, by leaving out the connecting flanges *b b*, shown in fig 2, so as to make one opening instead of the three shown.

The return flues L are plainly shown in fig. 1, connecting the sections with the ash-pit section B.

Instead of the lower section being made of metal, it can be made of brick or other suitable material, if desirable.

The pipes K K' K" K'' running from side to side of the cylinder, and parallel to each other, can be made of any desirable shape, either round, as shown, or elliptical or triangular, to prevent the accumulation of dirt or sediment of any kind.

The operation of my improved heating-apparatus is as follows:

The fires being started, the heat passes between the pipes K, as shown by the arrows, then down through the return flues L, and up through the outlet-pipe M and N.

If desired, a damper can be arranged in the top of the return-flues, when a direct draught is obtained instead of going through the return-flues.

It is often necessary when a slow generation of steam is desired, to close the dampers U, one of which can be arranged in each of the return-flues L or M, and one or all can, of course, be closed, when the heat passes directly to the chimney by opening the damper.

Having thus described my invention,

What I claim, and desire to secure by Letters Patent of the United States, is—

1. The heating-apparatus herein described, consisting of the hollow cylinder A, made in sections and provided with the pipes K K' K" and openings P, when constructed and arranged substantially as and for the purpose set forth.

2. In combination with the cylinder A, pipes K K" and openings P, the return-flue L provided with the dampers U, when arranged as herein described, and for the purpose set forth.

3. The combination and arrangement of the cylinder A, pipes K K' K", openings P, return flues L, with dampers U with the upper and lower outlets T and M, when all constructed substantially as herein shown and described, and for the purpose set forth.

ELIJAH M. BOSLEY.
